ROLLER SKATE

Clarence Vogt, Wenonah, N. J.

Application April 19, 1937, Serial No. 137,846

9 Claims. (Cl. 280—11.26)

This invention relates to new and useful improvements in roller skates and more particularly to skates of the type constructed and arranged to permit the person skating thereon to describe curves of substantially small radii.

The principal object of the present invention is to provide a skate of the character set forth, embodying certain improved structural features and arrangements together with novel means for absorbing shock imparted to the front wheel assembly or mounting by impact or collision with an object or obstruction for the purpose of preventing crystallization of the metal in the elements of said wheel assembly.

Another object of the invention is to provide a skate of the stated character constructed to include a member arranged to engage the surface being skated upon when the skate is tilted up onto the front wheel assembly for the purpose of preventing the forepart or tip of the foot support from contacting such skating surface.

Other features and objects of the invention and the details of construction thereof are set forth hereinafter and shown in the accompanying drawing, in which:

Figure 1 is a view in side elevation of a skate embodying the present invention.

Figure 2 is a partial view similar to Figure 1 showing the skate tilted up onto the front wheel assembly thereof.

Figure 3 is a view in section on line 3—3, Figure 1.

Figure 4 is a view in section on line 4—4, Figure 1, and

Figure 5 is a view in section on line 5—5, Figure 1.

Referring now to the drawing, a skate made in accordance with the present invention comprises front and rear foot supporting sections 1 and 2 respectively which are preferably, though not necessarily, constructed in accordance with the disclosure in my co-pending application Serial No. 81,325, filed May 22, 1936, and include axially extending depending ribs or folded portions 3 and 4 at the underside thereof, the inner ends of said portions being arranged for slidable telescopic engagement with each other in the manner described in said copending application.

In accordance with this invention, a bracket 6 is mounted beneath the front supporting section 1 and includes a forwardly declining flat portion 7 having flange portions 8 which project upwardly from opposite side edges thereof and terminate at their upper ends in outwardly projecting portions 9 through which said bracket 6

is secured to the underside of said section 1 by means of rivets or the like 10. As shown, the flat portion 7 projects forwardly a substantial distance and has its forward edge portion turned up or flanged as indicated at 11 to provide a flat end surface portion 12 for engagement with the surface over which the skate is travelling when said skate is tilted onto the front wheel assembly by the skater as illustrated in Figure 2 of the drawing, thus guarding against or preventing the fore part or tip of the supporting section 1 from contacting or scraping against such skating surface.

The front wheel assembly comprises a spindle supporting bracket 13 which includes upper and lower webs or portions 14 and 15 arranged in relatively spaced parallel relation with respect to one another and flanges 16 project upwardly from the opposite side edges of said uppermost web portion 14. These flanges 16 are arranged to reside outwardly adjacent the flange portions 8 of the bracket 6 and the spindle supporting bracket 13 is pivotally suspended from said bracket 6 by means of a shaft, pin or the like 18 which extends transversely of the skate through suitable openings formed in the flanges 8 thereof as well as said flanges 16 of said bracket 13. The pivotal movement thus afforded the bracket 13 is, however, quite limited and will be described in detail hereinafter.

As shown in Figure 1 of the drawing, the rear portion of the lower web 15 of the bracket 13 is upturned as at 19 and preferably secured to the rear end portion of the upper web 14 as indicated by reference numeral 20. The upturned portion 19 just mentioned is suitably notched or slotted at opposite sides thereof adjacent the web portion 15 as indicated at 21, the purpose for which will be set forth in detail hereinafter. The webs 14 and 15 of the bracket 13 are provided with aligned apertures 22 and 23 respectively and a spindle 24 is rotatably mounted therein. The flat portion 7 of the bracket 6 is similarly provided with an opening 25 therein to receive the upper extremity or tip of the spindle 24 and this opening 25 is sufficiently larger than the upper end of said spindle 24 to permit relative movement of the latter within said opening 25.

In the present instance, the lower end portion of the spindle 24 is of greater diameter than the upper portion thereof and the shoulder thus provided at the junction of these portions of different diameter is disposed adjacent the underside of the lower web portion 15 of the spindle bracket 13. As shown in the drawing, this lower end por-

tion of the spindle 24 of greater diameter extends through an opening 27 formed centrally of the tubular portion 28 of a bracket or like member 29 and an aperture or opening 30 is formed transversely of said spindle adjacent its lower end to receive therethrough a wheel axle or shaft 31 which is mounted in said tubular portion 28 of the bracket member 29, the usual wheels 32 being mounted upon opposite ends of said axle or shaft 31 in any suitable manner.

In the present instance, the inner end of the upper flange or web portion 33 of the bracket 29 is turned upwardly as indicated at 34 to a position adjacent and parallel to the upturned portion 19 of the lower web 15 of the spindle bracket 13 and this upturned portion 34 of bracket 29 is slotted or notched as at opposite sides thereof adjacent said web portion 33 as indicated by reference numerals 35, the arrangement being such that the upper projecting portions 36 of said portion 34 above the notches 35 therein function to positively limit rotation of the bracket 29 and spindle 24 by engaging the adjacent face of the upturned portion 19 of the spindle bracket 13 after said bracket 29 and spindle have pivoted or rotated a predetermined distance in either direction.

As shown particularly in Figure 4 of the drawing, the annular portions 37 of a pair of arms 38 loosely embrace the spindle 24 intermediate the supporting webs 14 and 15 of bracket 13 and these arms 38 engage or project through the slots or notches 21 and 35 at opposite sides of the upturned portions 19 and 34 of the brackets 13 and 29 respectively. An upstanding lug 39 is provided at the outer edge of each of the arms 38 and the inner edges of said lugs 39 are undercut or notched to receive the extremities of a spring 40 which is coiled about the spindle 24 and functions to yieldingly maintain said spindle 24, bracket 29 and wheels 32 in axial alignment yet permit the pivoting of these elements with respect to brackets 13 and 6 in a direction and degree depending upon the location and amount of pressure applied to the foot supporting sections 1 and 2 by the skater, the extent or degree of such pivotal movement being positively limited by the projecting portions 36 of the upturned portion 34 of bracket 29 which engage the upturned portion 19 of said bracket 13 as above described.

The upturned portion 19 of the bracket 13 extends between the arms 38 and functions as a centering means for the relative pivotable elements of the front wheel assembly when in normal position, and when these latter elements pivot in either direction, said upturned portion 19 maintains the opposite arm 38 in its normal position axially with respect to the skate while the other arm 38 is actuated by means of the upturned portion 34 of the bracket 29 which rotates with the spindle 24. This rotation occurs against the action of the spring 40 and by maintaining the other arm 38 in its normal position the extent of compression of the spring 40 is increased, thus building up a greater force in said spring 40 for the purpose of returning the pivoted elements of the wheel assembly to their normal position axially of the skate.

For the purpose of absorbing shock imparted to the wheel assembly and preventing crystallization of the metal in the various component parts thereof caused by impact or collision of the wheels 32 with relatively stationary or heavy objects or obstructions, a pair of lugs 41 are

formed at the rear end of the upper web 14 of the bracket 13 and these lugs 41 are turned upwardly substantially at right angles to said web and extend to within a short distance of the under surface of the front foot supporting section 1 as shown in Figure 2 of the drawing. The lugs 41 are each surrounded by a coil spring 42 which acts between the upper surface of the upper web 14 and the under surface of the supporting section 1 as shown in Figure 5 to absorb shocks imparted to the front wheel assembly, the pivotal suspension of said bracket 13 from the bracket 6 effected through the pin 18 permitting the bracket 13 and wheel assembly to pivot slightly relative to said bracket 6 against the yielding resistance afforded by the springs 41. Pivotal movement of the bracket 13 and wheel assembly is quite restricted, however, as clockwise movement thereof with respect to the drawing is positively limited by engagement of the forward edge portion of the upper web 14 of said bracket with the underside of the flat portion 1 of the bracket 6 while movement in the opposite or counterclockwise direction is positively limited by engagement of the upper extremities of the lugs 41 with the underside of the foot section 1 but between these fixed limits pivotal movement of the bracket 13 and wheel assembly is permitted against the yielding resilience of the springs 42 which tend to urge these members in the first mentioned or clockwise direction and effectively function to absorb, at least in part, any shock or impact upon the front wheel assembly of the skate.

While a particular embodiment of the invention has been set forth herein for descriptive purposes, it is not intended that said invention shall be precisely limited thereto but that modifications and changes may be incorporated and embodied therein within the scope of the annexed claims.

I claim:

1. In a skate including a foot support, a bracket secured to the underside of said foot support, a spindle support pivoted to said bracket for limited movement in a plane substantially perpendicular to the plane of the foot support, a spindle rotatably mounted in said spindle support, a wheel-axle rotatable with said spindle, mechanism tending to resist rotation of said wheel axle and spindle relative to the spindle support, and means constantly urging said spindle support forwardly of the skate and operative to yieldingly resist rearward movement of the spindle support and absorb shocks received thereby and effecting such movement.

2. In a skate including a foot support, a bracket secured to the underside of said foot support, a spindle support pivoted to said bracket for limited movement in a plane substantially perpendicular to the plane of the foot support, a spindle rotatably mounted in said spindle support, a wheel axle rotatable with said spindle, mechanism tending to resist rotation of said wheel axle and spindle relative to the spindle support, means forming a part of said spindle support arranged to positively limit pivotal movement thereof, and means constantly urging said spindle support forwardly of the skate and operative to yieldingly resist rearward movement of the spindle support and absorb shocks received thereby and effecting such movement.

3. In a skate including a foot support, a bracket secured to the underside of said foot support, a spindle support pivoted to said bracket for lim-

- ited movement in a plane substantially perpendicular to the plane of the foot support, a spindle rotatably mounted in said spindle support, a wheel axle rotatable with said spindle, mechanism tending to resist rotation of said wheel axle and spindle relative to the spindle support including means for positively limiting said rotation of the wheel axle and spindle, means forming a part of said spindle support for positively limiting pivotal movement thereof, and means constantly urging said spindle support forwardly of the 10 skate and operative to yieldingly resist rearward movement of the spindle support and absorb shocks received thereby and effecting such movement.
4. In a skate including a foot support, bearings mounted below said foot support for limited pivotal movement in a plane substantially perpendicular to the plane of the foot support, a spindle 20 rotatably mounted in said bearings, a wheel axle rotatable with said spindle, and means constantly urging the bearings forwardly of the skate and operative to yieldably resist rearward movement of the bearings and absorb shocks received thereby and effecting such movement.
5. In a skate including a foot support, bearings mounted below said foot support for limited pivotal movement in a plane substantially perpendicular to the plane of the foot support, a spindle 30 rotatably mounted in said bearings, a wheel axle rotatable with said spindle, means constantly urging the bearings forwardly of the skate and operative to yieldably resist rearward movement of the bearings and absorb shocks received thereby and effecting such movement, and mechanism tending to resist rotation of the wheel axle and spindle relative to said bearings.
6. In a skate including a foot support, bearings mounted below said foot support for limited pivotal movement in a plane substantially perpendicular to the plane of the foot support, a spindle 40 rotatably mounted in said bearings, a wheel axle rotatable with said spindle, means constantly urging the bearings forwardly of the skate and operative to yieldably resist rearward movement of the bearings and absorb shocks received thereby and effecting such movement, and means forming a part of said bearings for positively limiting pivotal movement thereof.
7. In a skate including a foot support, a bracket secured to the underside of said foot support adjacent the toe end thereof and including a forwardly declining substantially flat portion for engagement with a skating surface in certain positions of said skate to prevent engagement of such surface by said toe end of the foot support, a front wheel assembly pivotally carried by said bracket constructed and arranged for limited movement relative thereto in a plane substantially perpendicular to the plane of said foot support, and means constantly urging said wheel assembly forwardly of the skate and bracket and operative to yieldingly resist rearward movement 10 of the wheel assembly and absorb shocks received thereby and effecting such movement.
8. In a skate including a foot support, a bracket secured to the underside of said foot support adjacent the toe end thereof and including a forwardly declining substantially flat portion for engagement with a skating surface in certain positions of said skate to prevent engagement of such surface by said toe end of the foot support, a front wheel assembly pivotally carried by said bracket constructed and arranged for limited pivotal movement relative thereto in a plane substantially perpendicular to the plane of said foot support, said wheel assembly including mechanism operative to permit rotation of the wheels 20 thereof in a plane substantially perpendicular to the plane of the pivotal movement of the wheel assembly relative to the bracket, and means constantly urging said wheel assembly forwardly of the 25 skate and bracket and operative to yieldingly resist rearward movement of the wheel assembly and absorb shocks received thereby and effecting such movement.
9. In a skate including a foot support, a bracket secured to the underside of said foot support adjacent the toe end thereof and including a forwardly declining substantially flat portion for engagement with a skating surface in certain positions of said skate to prevent engagement of such surface by said toe end of the foot support, a front wheel assembly pivotally carried by said bracket constructed and arranged for limited movement relative thereto in a plane substantially perpendicular to the plane of said foot support, and means constantly urging said wheel assembly forwardly of the 35 skate and bracket and operative to yieldingly resist rearward movement of the wheel assembly and absorb shocks received thereby and effecting such movement, and means forming a part of said wheel assembly for positively limiting pivotal movement thereof.

CLARENCE VOGT.
